RAILWAY COUPLER OPERATING ROTOR
 Loree Elwyn Furniss, Groveport, Ohio, assignor to The
 Buckeye Steel Castings Company, Columbus, Ohio
 Filed Oct. 29, 1956, Ser. No. 618,740
 2 Claims. (Cl. 213—168)

The present invention relates to a railway coupler of the knuckle type wherein the anticreep mechanism is released and the lock raised and the knuckle shifted to an open position upon rotation of the rotor and the invention more specifically pertains to the structure of the outer end of the rotor and its connection with the coupler operating rod.

In service and when there is a structural failure so as to make it possible for a type F coupler to be pulled away from the body structure of a railway vehicle such outward movement of the coupler causes the standard rotor to be turned and in a direction of rotation to free the anticreep and to lift the lock sufficiently for the knuckle to swing to an open position. When the knuckle of the pulled out coupler is unlocked and when the other coupler is of the interlocking type such features become ineffective and it is possible for the coupler to drop to the road bed. Efforts have been made to improve the connection between the rotor and the coupler operating rod to avoid undesired rotation of the rotor when there is an increase in the angle between the operating rod and the center line of the motor such as occurs when there is a pull out of a coupler.

It is an object of the invention to provide further improvements in the connection between the rotor and the operative rod and structure of a rotor for a lock operating mechanism whereby the rotor will not be rotated when the angle between the axis thereof and the center line of the operating rod increased during outward movement of the coupler with respect to the vehicle body and to provide a structure which may be conveniently manufactured in a casting operation and a rotor which is of materially less weight.

It is an object of the present invention to provide structural characteristics at the outer end of the rotor for connection with the operating rod wherein undesired unlocking of the coupler is avoided on pull outs and wherein the bearing area for the support of the operating rod is materially increased and the rate of wear is materially reduced.

Other objects and features of the invention will be appreciated and become apparent as the present disclosure proceeds and upon consideration of the accompanying drawing and the following detailed description wherein an embodiment of the invention is disclosed.

In the drawing:

FIG. 1 is a perspective view of a lock operating rotor for a railway coupler exhibiting the invention.

FIG. 2 is a plan view of the rotor showing a conventional coupler operating rod in association therewith in the inactive position of the rod with the phantom lines indicating the position of the inner end portion of the coupler operating rod in position to be engaged with and disengaged from the rotor.

FIG. 3 is an elevational view taken from the rear side of the rotor and the operating rod which is shown in the inactive position.

FIG. 4 is an end view of the rotor with a portion of the operating rod shown in section and in the inactive position thereof whereas the phantom lines represent the position of the inner end of the operating rod with the knuckle open and the handle of the operating rod against its stop.

The invention pertains to the structural characteristics of the outer end portion of the rotor for the lock operating mechanism for a railway coupler. The rotor includes

2

a shaft shaped portion 10 having a lug 11 projecting therefrom and provided with flat side surfaces 12 and 14. The shaft portion of the rotor and the structure of the lug 11 are of conventional construction and the rotor disclosed while being particularly adapted for the type F coupler may be adapted for use in other couplers and equipped with an outer end structure formed in accordance with the present invention.

The structural characteristics at the outer end of the 10 rotor are such that the hook or J-shaped end 16 of conventional type of coupler operating rod 17 may be arranged therein for actuating the rotor during an intentional lock lifting operation to swing the knuckle of the coupler to an open position. The structure shown to the right in FIG. 1 may be formed integral with the shaft portion 10 and one of the advantages of the present invention is that the entire rotor may be formed in a casting operation wherein the pattern parting may be formed along the line 19 (FIG. 4).

The structure at the outer end of the rotor includes an inner end wall 21 arranged substantially at right angles to the axis of the shaft portion 10. The free edge 22 of the wall 21 is arranged in a plane which is substantially tangential to the periphery of the shaft portion 10 15 of the rotor. A bottom member or wall 24 is arranged substantially at right angles to the wall 21 and an arcuate portion 26 joins the wall 24 with the wall 21. The free edges of the wall 24 and the arcuate wall portion 26 are in the plane of the edge 22 of the wall 21. An outer end 20 wall 27 occupies a plane substantially at right angles to the bottom member or wall 24. The wall 27 preferably is integral with the wall 24 and the free edge 28 of the wall 27 is in the same plane as the edge 22 of the wall 21. An aperture 29 is provided in the end wall 27.

A front wall 31 is arranged in a plane substantially parallel to the edges 22 and 28 of the end walls and in a plane substantially at right angles to the end wall 27. The inner surface of the wall 31 is flat throughout the central area but has arcuate portion 25 which merges 35 with the wall 21 and the arcuate wall portion 26.

The hook or J-shaped end 16 of the coupler operating rod is retained in the cavity provided by such walls during normal operating conditions by a ledge 33 which does not completely form a roof over the cavity. The 40 ledge 33 is carried principally by the end wall 27 although the forward portion of the ledge may be integral with the outer end portion of the wall 31. The inner edge 34 of the ledge 33 adjacent the wall 31 is in a vertical plane and is substantially parallel with the end wall 27. This parallel surface 34 merges at 36 with the edge surface 37 on the ledge 33. The surface 37 while remaining in a generally vertical plane converges towards the wall 27 in proceeding rearwardly from the area 36. The inclined surface 37 merges with the inner surface 50 of the wall 27 at the rear end thereof as best shown in FIG. 2.

An under surface 39 on the ledge 33 inclines upwardly in proceeding rearwardly from the wall 31 and the inclination of this surface 39 is shown in dotted lines in 55 FIG. 4. The purpose of the inclined surface 39 is to allow the J-shaped or hook-shaped end 16 of the coupler operating rod to rotate within the rotor after the knuckle of the coupler has been swung to an open position by the operating rod and when the handle is then dropped so that it moves back against its stop on the supporting bracket at the side and end of the railway vehicle body.

The upper surface of the ledge 33 is flush with the top edge of the end wall 27 so as to provide a relatively large bearing area for the support of the coupler operating 60 rod 17 in its inactive position. The upper surface of the ledge 33 and the top edge of the end wall 27 in the rear area 41 (FIG. 4) is in a single plane which is substan- 70

tially parallel to the wall 24. The upper surface of the ledge 33 and the top edge of the end wall 27 in the area 42 slope downwardly from the surface area 41 in proceeding towards the wall 31 and the front of the rotor. The inclination of the area 42 continues to provide an inclined edge 43 on the wall 31.

The structure at the end of the rotor includes a lug 46 which is integral with the wall 21 in the vicinity of the end of the shaft portion 10. This lug extends from the wall 21 towards the end wall 27 and terminates in an end surface 47 spaced from the end wall 27. An inner portion of the lug 46 is rounded as indicated at 48. The thickness of the lug increases in proceeding towards the free end thereof for the purpose of increasing the strength of the lug. The lug includes an arcuate portion 49 where it merges with the inner surface of the wall 21.

The inactive position of the rotor is represented in FIG. 2. The hook or J-shaped end 16 of the coupler operating rod 17 may be mounted in operative association with the rotor within the cavity by arranging the coupler operating rod in the phantom line position shown in FIG. 2. Thereafter the coupler operating rod 17 may be swung to the position shown in full lines in FIG. 2 when the outer end of the coupler operating rod is then in position to be secured in the bracket at the end and side of the railway vehicle body.

The inactive position of the coupler operating rod when viewed from the rear thereof is shown in FIG. 3 and it will be noted that the free end of the hook or J-shaped end 16 is then within the cavity and positioned beneath the ledge 33. If there is an outward movement of the coupler as a result of failure of the draft rigging or some part of the coupler the rotor will move in the direction of the arrow 63 in FIG. 2. The coupler operating rod while pivoting about the bracket at the outer side of the vehicle body will then swing relative to the axis of the rotor towards the phantom line position shown in FIG. 2 and the structure at the outer end of the rotor permits such movement without any tendency of the rotor to be turned. When the operating rod arrives in the phantom line position shown in FIG. 2 the hook is free to disengage from the rotor upon further outward movement of the coupler. Thus there is no tendency of the rotor being turned so as to lift the lock when there is a pull-out of the coupler. The pulled coupler then remains in mated coupled relationship with the coupler of the other car or vehicle.

In operation and when it is desired to free the anticerip mechanism of the coupler and to lift the lock the coupler operating rod is rotated in the direction of the arrow 62 in FIG. 4. The reversely disposed portion of the hook or J-shaped end 16 of the coupler operating rod then engages the inner surface of the wall 31. The portion 63 of the coupler operating rod then engages the inner surface of the lug 46. The shaft like portion 10 is then rotated in the direction of the arrow 64 (FIG. 1) to carry out the lock lifting and knuckle throwing operation.

When the knuckle is in the open position and when the handle of the coupler operating rod is permitted to return to its inactive position against the stop on the bracket carried by the railway vehicle body the lock operating parts are free to return by gravity and the rotor and the hook-shaped end of the operating rod assume the relationships shown in phantom lines in FIG. 4 when the portion 63 of the hook or J-shaped end lies along the inclined area 42. The free end of the hook shaped portion is then adjacent the inclined under surface 39 of the ledge 33.

While the invention has been described with reference to a rotor for one type of interlocking coupler it will be appreciated that the structural characteristics forming the outer end of the rotor may be applied to other types

of lock operating parts and that changes may be made in the structural features at the outer end of the rotor. Such modifications and others may be made without departing from the spirit and scope of the invention as set forth in the appended claims.

What I claim and desire to secure by Letters Patent is:

1. A rotor for the lock operating mechanism of a railway coupler comprising, a shaft portion, an inner wall carried by an outer end of said shaft portion arranged in a plane substantially at right angles to the axis of said shaft portion, an outer wall substantially parallel to said inner wall and spaced therefrom, a front wall and a bottom member both joining said inner and outer walls, a ledge carried by said outer wall projecting inwardly therefrom and extending from the front wall to the rear edge of said outer wall, an undersurface on said ledge substantially at right angles to said outer wall forming a downwardly facing abutment preventing upward movement of the free end of a hook shaped coupler operating rod, a first inner side surface on said ledge substantially parallel to said outer wall in an area adjacent the front wall, another inner side surface on said ledge arranged in one plane converging towards the outer wall in proceeding rearwardly from a rear end of the first inner side surface, a lug carried by said inner wall extending substantially parallel to said shaft portion towards said outer wall, said second inner side surface on said ledge being spaced from a free end of said lug to accommodate the hook shaped end of the operating rod therebetween, a forwardly facing surface on said lug forming an abutment for the coupler operating rod during intended rotation thereof, and the upper surface of said ledge being flush with the upper edge of said outer wall forming a bearing surface supporting the coupler operating rod in the inactive position.

2. A rotor for the lock operating mechanism of a railway coupler comprising, a shaft portion, an inner wall carried by an outer end of said shaft portion arranged in a plane substantially at right angles to the axis of said shaft portion, an outer wall substantially parallel to said inner wall and spaced therefrom, a front wall and a bottom member both joining the inner and outer walls, a ledge carried by said outer wall projecting inwardly therefrom, an undersurface on said ledge extending from the front wall to a rear edge of the outer wall arranged substantially at right angles to said outer wall forming a downwardly facing abutment limiting upward movement of a free end of a hook shaped coupler operating rod, a first inner side surface on said ledge substantially parallel to said outer wall in an area adjacent said front wall, a lug extending from an upper rear portion of said inner wall towards said outer wall, a forwardly facing generally vertical surface on said lug forming an abutment for the coupler operating rod during intended rotation thereof, a second inner side surface on said ledge arranged in one plane converging towards said outer wall in proceeding rearwardly from the rear end of the first inner side surface, said second inner side surface being spaced from a free end of said lug providing a passageway for the escape of the coupler operating rod therethrough with the second inner side surface forming a guide for the coupler operating rod during escape through said passageway, an upwardly facing surface on said outer wall flush with an upper surface on said ledge forming a bearing supporting the coupler operating rod in the inactive position, and the undersurface on said ledge converging towards the upper surface on said ledge in proceeding rearwardly providing clearance for the free end of said hook shaped end of the coupler operating rod when the coupler is in the open position.
